(57) **CLAIM**

The ornamental design for a filter insert for hydraulic fracturing filter housing, as shown and described.

DESCRIPTION

FIG. 1 is a front perspective view of a filter insert for hydraulic fracturing filter housing.

FIG. 2 is another perspective view of the filter insert for hydraulic fracturing filter housing of FIG. 1.

FIG. 3 is a bottom perspective view of the filter insert for hydraulic fracturing filter housing of FIG. 1.

FIG. 4 is a front view of the filter insert for hydraulic fracturing filter housing of FIG. 1; the rear is a mirror image thereof.

FIG. 5 is a side view of the filter insert for hydraulic fracturing filter housing of FIG. 1; the other side is a mirror image thereof.

FIG. 6 is a top view of the filter insert for hydraulic fracturing filter housing of FIG. 1; and,

FIG. 7 is a bottom view of the filter insert for hydraulic fracturing filter housing of FIG. 1.

1 Claim, 7 Drawing Sheets
